(57) **CLAIM**

The ornamental design for an injector cartridge, as shown and described.

DESCRIPTION

FIG. 1 is a side perspective view of an injector cartridge design;

FIG. 2 is a front side view of the injector cartridge shown in FIG. 1, the rear side view being a mirror-image thereof;

FIG. 3 is a right-side view of the injector cartridge shown in FIG. 1, the left-side view being a mirror-image thereof;

FIG. 4 is a top plan view of the injector cartridge shown in FIG. 1;

FIG. 5 is a bottom plan view of the injector cartridge shown in FIG. 1; and,

FIG. 6 is a bottom perspective view of the injector cartridge shown in FIG. 1.

1 Claim, 5 Drawing Sheets
